UNITED STATES PATENT OFFICE.

EUGENE D. DOLLOFF, OF BOSTON, MASSACHUSETTS.

DESIGN FOR AN AUTOMOBILE TAG.

Application filed March 19, 1927. Serial No. 21,207. Term of patent 14 years.

To all whom it may concern:

Be it known that I, EUGENE D. DOLLOFF, a citizen of the United States, residing at Boston, in the county of Suffolk, State of Massachusetts, have invented a new, original, and ornamental Design for Automobile Tag, of which the following is a specification, reference being had to the accompanying drawings, forming a part thereof.

In the drawings Fig. 1 is a plan view of a tag showing my new design. Fig. 2 is an edge view. The drawing is lined for color.

What I claim is:

The ornamental design for an automobile tag, as shown and described.

EUGENE D. DOLLOFF.
